UNITED STATES PATENT OFFICE.

REGINALD A. FESSENDEN, OF PITTSBURGH, PENNSYLVANIA, ASSIGNOR, BY DIRECT AND MESNE ASSIGNMENTS, TO THE NATIONAL ELECTRIC SIGNALING COMPANY, OF PITTSBURGH, PENNSYLVANIA, A CORPORATION OF NEW JERSEY.

SIGNALING BY ELECTROMAGNETIC WAVES.

1,020,032.

Specification of Letters Patent. Patented Mar. 12, 1912.

Application filed July 27, 1903. Serial No. 167,242.

To all whom it may concern:

Be it known that I, REGINALD A. FESSENDEN, a citizen of the United States, residing at Pittsburgh, in the State of Pennsylvania, have invented certain new and useful Improvements in Signaling by Electromagnetic Waves, of which the following is a specification.

The invention herein described relates to 10 the transmission and receipt of the energy of electro-magnetic waves and more particularly to improvements in the antennæ used for receiving or transmitting the energy of electro-magnetic waves.

15 In the accompanying drawing Figures 1 and 2 show diagrams of forms of construction respectively of receiving and sending apparatus according to my invention. Figs. 3 and 4 show side elevations of antennæ 20 mounting, the latter being a modification.

In Fig. 1, 5, 5 is a horizontal wire or bundle of wires, preferably of iron, preferably insulated, and preferably of small diameter, for example No. 40 B. & S. gage. 25 This wire or bundle of wires is extended horizontally as shown in Fig. 3 and may either rest upon the ground or as there shown is preferably supported at a short distance from the ground, for example two 30 feet, by the insulators 23, 24, on posts 21, 22. When this form of antenna is used for receiving messages, a coil or coils 6, 7, are wound around it, preferably near its center, and the terminals of the coil or coils are 35 connected to a receiver 8 which may be a barretter. 10 is an indicating device which may be a telephone, and 11 a potentiometer means of adjusting the potential in the local circuit 11, 8, 10. The circuit 8, 6, 9, 7, is 40 preferably tuned to the periodicity of the wave which it is desired to receive, and for this purpose the condenser 9 may be used. When this form of antenna is used for sending, as shown in Fig. 2 it is surrounded, 45 preferably near its center, by a coil 14 which with the condensers 16', 16, and the spark gap 18, forms a circuit for producing oscillations of the desired frequency. 19 is an induction coil and 20 a local battery for operating the induction coil. 17 is a key which on being depressed cuts out a portion of the capacity 16, and changes the period of the oscillations, and which may also be used as a signaling key which operates by throw-

ing the sending station in and out of tune 55 with the receiving station.

Where a bundle of iron wires is used the bundle may either be compact as shown in Fig. 1, or may be spread out into a fan shape as shown in Fig. 2. Fig. 2 shows 60 a plan view of the type of antenna and Fig. 3 shows a side view, where 12, 13, is the antenna, 14 a coil of wire wrapped around it and 15 either the receiving or sending apparatus. G shows the ground 65 level and 23, 24 are insulators which may be used for supporting the antennæ.

It is to be noted that in the apparatus shown the magnetic or horizontal component of the electro-magnetic waves is utilized instead of the vertical or electro-static component. It is also to be noted that the length of the bundle of iron wires is preferably adjusted so that it is in tune with the wave length of the waves which it is 75 desired to generate or receive.

It is found that a receiving antenna of this form responds only to waves impinging upon it laterally and is not responsive to waves reaching it in the direction in 80 which it lies, hence this form of antenna may be arranged so as to rotate about a vertical axis 26 as in Fig. 4, and be made unresponsive to impulses emanating from a given direction. This method is therefore 85 of use for selective working, and for determining the direction from which the impulses are sent. By the use of a horizontal reflector 27, arranged parallel with the bundle of iron wire 12, 13, and supported 90 on the wire support 25, as shown in Fig. 4, impulses may be received from one direction only, and this is specifically useful where it is desired to locate accurately the direction from which received impulses are sent. It 95 may also be used for sending strengthened impulses in one direction.

Having thus described my invention and illustrated its use, what I claim as new and desire to secure by Letters Patent, is the 100 following:

1. Apparatus for sending or receiving energy by electro-magnetic waves, comprising an antenna formed of wires of magnetic material extending horizontally in proximity to the ground and adapted to operate by directly utilizing the electromagnetic component of the waves. 105

2. Apparatus for the receipt and transmission of electromagnetic wave energy, comprising an antenna formed of a close bundle of wires, supported horizontally in proximity to the ground and adapted to directly utilize the electromagnetic component of the waves.
3. An antenna for transmission and receipt of electromagnetic wave energy, comprising a close bundle of wires arranged horizontally and adapted to operate directly by the electro-magnetic component of the waves, and supported to be rotated in a horizontal plane.
4. An antenna for transmission and receipt of electro-magnetic wave energy, formed of wires placed horizontally in proximity to the ground, combined with a horizontally arranged reflector, substantially as described.
5. An antenna for transmission and receipt of electro-magnetic wave energy, comprising a horizontal wire, a horizontally pivoted support therefor combined with a reflector mounted parallel with the wire, substantially as described.
6. In wireless telegraphy, the combination of a magnetic antenna, a receiver and a coil adapted for receiving by the effects of the magnetic component of the electromagnetic waves, and a condenser in circuit with said coil.
7. In wireless telegraph apparatus an antenna composed of horizontal wires placed in the plane of polarization of the waves and rotatably mounted, combined with means to directly utilize principally the effects of the electromagnetic component of the waves, substantially as described.
8. Apparatus for signaling by electromagnetic waves comprising an antenna placed in position to be most affected by the electromagnetic component of the waves, and made of magnetic material, combined with a coil surrounding said antenna and forming part of the signaling apparatus.

Signed at Washington in the District of Columbia this 27th day of July, A. D. 1903.

REGINALD A. FESSENDEN.
